UNITED STATES PATENT OFFICE

2,351,076

METHOD OF POUNCING HATS

Paul Schultze, Danbury, Conn., assignor to John C. Doran, doing business as Doran Brothers, Incorporated, Danbury, Conn.

Original application August 24, 1938, Serial No. 226,442. Divided and this application December 1, 1939, Serial No. 307,039

10 Claims. (Cl. 223—20)

This invention relates to a method of pouncing or finishing hat bodies.

One of the objects of this invention is to provide a method for finishing hat bodies which is simple, efficient and capable of being effectuated by untrained personnel. Another object is to provide a method of the above nature capable of imparting a smooth velvety and uniform finish to a hat without the production of any tool marks thereon. Other objects will be in part apparent and in part pointed out hereinafter.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the accompanying drawings in which is shown several embodiments of my invention,

Figure 1 is a fragmentary side elevation of a modified form of a machine for carrying out my method;

Figure 2 is an enlarged fragmentary elevation partly in section of the tool shown in Figure 1 operating on a hat mounted on the hat block; and,

Figure 3 is an enlarged fragmentary sectional elevation of the hat block supporting and operating head of the machine shown in Figure 1. This view also is illustrative of a modification of the machine shown in Figure 1.

Similar reference characters refer to similar parts throughout the various views of the drawings. This application is a division of my co-pending application Serial No. 226,442, filed August 24, 1938, entitled "Pouncing machine," which issued on October 28, 1941, as United States Patent No. 2,260,956.

While the machine described in my above-noted patent is particularly well adapted to pouncing blocked hats, it is necessary to pounce unblocked hats, particularly hat bodies being prepared for the manufacture of women's hats. Such hat bodies often have no definite head size, and often are quite deep and generally conical in shape. Hat bodies of this nature accordingly preclude the mounting thereof on conventional hat blocks turned to a definite head size for conformation. Therefore, to obviate the difficulties encountered in hand pouncing such hat bodies, the pouncing machine shown in Figure 1 is directed. In general organization, this machine is similar to that shown in my above-noted patent,

and accordingly includes column 19 comprising base 11, a motor housing 12 and extension 13. However, a special head generally indicated at 111 is mounted on extension 13 and this head rotatably mounts a spindle 112 driven by motor 23 through pulleys 113, 114 and belt 115. As is more clearly shown in Figure 3, spindle 112 is rotatably mounted in a journal 117 and is slidably mounted for rotation and also axial movement within a journal 111a, the spindle having associated therewith clutch mechanism generally indicated at 118 which is operated by engaging and disengaging apparatus generally indicated at 119. For a detailed description of the details of construction and operation of the spindle clutch and its operating mechanism, reference is made to my United States Patent No. 2,105,130.

The left-hand end of spindle 112, as viewed in Figure 3, has secured thereto a back support generally indicated at 120 having a tubular hub portion 121, which carries anti-friction bearings 122 and 123 in which a reduced end 112a of spindle 112 is rotatably mounted. The lower end of back support 120 has a boss 124 in which is secured an end 125a of a rod 125, to the other end of which a piston 126 is attached. Piston 126 is adapted to reciprocate in a cylinder 127 secured to head 111, as oil under pressure is fed into one end or the other of the cylinder, as particularly described in my above-noted U. S. Patent No. 2,105,130. When piston 126 is actuated, as noted in my patent, spindle 112, and accordingly support 120, are moved axially and this for a purpose to be described.

The extreme end 112b of spindle 112 is further reduced and has secured thereto so as to rotate therewith a spider 128. The right-hand end of spider 128, as viewed in Figure 3, is formed in an annulus or ring 129 and has secured thereto a block 130 as by screws 131, block 130 having a generally frusto-conical shape. The outer surface of the block is covered preferably with a piece of felt 132 or the like. Back support 120 at its larger end 120a is annular and has attached thereto a hood 133 by bolts 134.

As is more clearly shown in Figure 1, hood 133 has an enlarged slot 135 formed therein and extending from near the base of the hood over the tip or rounded end of the hood, so as to expose a substantial portion of felt covered block 130. Hood 133 is so mounted that slot 135 is arranged in registry with pouncing tool 30 so that when the tool traverses a hat body mounted on the hood, it travels in a path extending from the tip of the hat toward the brim thereof. As noted

above, however, the hat body is often of substantial depth, and accordingly extends farther over hood 133 than the limit of traverse of the tool therealong. It is for this reason that axial movement of hat block spindle 112 and the parts attached thereto are axially movable. Thus, as described in my U. S. Patent No. 2,105,130, after the tool has reached the extent of its travel, the spindle, and accordingly hood 133 is automatically actuated to move the hat body past the tool as the tool continues to operate until all portions of the hat have been pounced, and thereafter reverse the movement of the hat back to the point where reversal of the movement of the tool is automatically begun.

Heretofore hat manufacturers have been unable to automatically pounce all portions of the hat in a continuous operation at a uniform rate. This is, of course, desirable as it not only expedites the finishing of the hat, and accordingly reduces the cost thereof, but also imparts to the hat a finish far superior to that attained by hand pouncing or other known methods. It has usually been the practice to remove the hat from the machine after the crown has been pounced, and thereafter finish the brim on a special brim pouncing machine. In accordance with the method of pouncing contemplated herein, however, the hat is pounced from its tip to the outer edge of its brim in one continuous operation and at a uniform rate, thus leaving no tool marks between the hat tip and brim edge as would otherwise be the case, and eliminating the separate brim pouncing operation with the loss of time and labor attendant thereto. Thus, by rotating the hat at a uniform speed and pouncing the outer surface of the rotating hat continuously and at a uniform rate along a path extending from the tip of the hat to the outer edge of the brim thereof, all without removing the pouncing pad therefrom, a superior finish is imparted to the hat and substantial savings in the cost of manufacture thereof are effected.

In view of the fact that hat bodies pounced on the machine just described vary substantially in head size, I have provided means for holding the hat in a position where the tool can operate on it and also for feeding the hat past the elliptically moving tool. This holding and feeding mechanism, as shown in Figures 1 and 2, comprises a system of piping 136 connected to a suitable source of compressed air, and connected at its upper end to a header 137 from which a pair of pipes 138 and 139 lead respectively to T's 140 and 141. Each of these T's has connected thereto a pair of pipes 142 and 143 which terminate in nozzles or jets 144 and 145, respectively, at the bottom and top edges of pouncing pad 30a and adjacent the operative surface thereof. As is best shown in Figure 2, nozzles 144 and 145 are so directed that blasts of air issuing therefrom impinge against a hat 146 mounted on hood 133 at points respectively adjacent the lower and upper edges of hood slot 135. The air issuing from jets 134 and 135 is of sufficient pressure to blow hat 146 firmly enough against felt covered block 130 so that the hat adheres thereto as the block rotates. Thus hat 146 is rotated, for example, in the direction of the arrow, and as its lower portion 146a moves over the bottom edge of slot 135, the air pressure from nozzles 144 forces it against felt covered block 130. Similarly, as upper portion 146b of the hat moves against the upper edge of slot 135, the hat is peeled from the hat block so as to ride over the outer surface of hood 133.

Hence, it may be seen that that part of the hat between portions 146a and 146b thereof is held against the rotating hat block in a position where it may be worked on by pouncing tool 30.

If for any reason the hat body 146 is not of sufficient depth to completely cover slot 135 shown in Figure 1, a suitable shutter or the like (not shown) may be provided for hood 133 to cover that portion of slot 135 not covered by the hat body. Air pipes 136 may be connected in any suitable manner to tool assembly 28 and have any type of suitable connection such as ball and socket joints or flexible tubing, which will not interfere with the free swiveling of the tool assembly. Furthermore, by the provision of the symmetrically placed nozzles 144 and 145, i. e. symmetrical with respect to pouncing pad 30a, the air pressure against the hat on each side of the pouncing pad is substantially equal and accordingly tends to keep the pad in proper tangential position with respect to the hat block without, however, adversely affecting free swiveling of the pouncing tool.

Under certain circumstances, it may be desirable to hold the hat body against hood 135 by negative pressure instead of positive pressure. In view of the fact that the only opening in hood 133 is that provided by slot 135, a partial vacuum can be maintained within the hood when a hat body is placed thereover so as to cover the slot. This partial vacuum has the same effect in holding a hat body against block 130 as does the positive pressure exerted by the jets directed against the outer surface of the hat body. Hence, with reference to Figure 3, I have provided a pipe fitting 147 registering with an opening 148 in back support 120. Any suitable piping (not shown) may be connected to fitting 147 and with any suitable evacuating system. If desired, a pump (not shown) may be disposed within column extension 13 or elsewhere in or on the machine and pneumatically connected with fitting 147 and accordingly with the inside of hood 133. It follows, that upon operation of such a pump, air is sucked from within the hood, and a hat disposed thereon is pulled against block 130 so as to rotate therewith as hereinbefore described.

Accordingly I have provided a method of pouncing hat bodies which accomplishes the various objects hereinbefore set forth in a thoroughly practical and efficient manner.

As many possible embodiments may be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

I claim:

1. The method of pouncing a hat which includes the steps of, supporting the hat closely adjacent but out of contact with a rotating block, forcing a portion only of the hat against the block to effect rotation of the hat, and continuously abrading the rotating hat along a path extending from the tip to the brim edge of the hat.

2. The method of pouncing a hat which includes the steps of, supporting the hat closely adjacent but out of contact with a rotating block, forcing a portion only of the hat against the block to effect rotation of the hat, and continuously abrading the rotating hat at a uniform rate along a path extending from the tip of the hat to the brim edge of the hat.

3. The method of pouncing a hat which includes the steps of, supporting the hat closely adjacent but out of contact with a rotating block, forcing a portion only of the hat against the block to effect rotation of the hat, and continuously abrading the rotating hat at a uniform rate along a path extending from the tip of the hat to the brim edge of the hat and back again over the same path.

4. The method of pouncing a hat which includes in the order named the steps of, supporting a hat, forcing a portion only of the hat against a rotating block to effect rotation of the hat, engaging the hat with an abrading tool immediately adjacent that portion of the hat being forced against the block, and effecting relative movement between the abrading tool and the hat so that the hat is pounced along a path extending from the tip of the hat to the brim edge of the hat.

5. The method of pouncing a hat which includes in the order named the steps of, loosely supporting the hat adjacent a rotating member, forcing a portion of the hat against said member to create a driving relation therebetween and accordingly rotate the hat, engaging the hat with an abrading tool immediately adjacent that portion of the hat which is in engagement with said member, and relatively moving the abrading tool and the hat to pounce the hat.

6. The method of pouncing a hat which includes in the order named the steps of, loosely supporting the hat adjacent a rotating member, forcing a portion of the hat against said member to create a driving relation therebetween and accordingly rotate the hat, engaging the hat with an abrading tool immediately adjacent that portion of the hat which is in engagement with said member, and moving the abrading tool over the hat along a path extending between the tip and brim edge of the hat.

7. The method of pouncing a hat which includes in the order named the steps of, supporting a partially blocked hat adjacent a rotating member so that the brim of the hat extends out-

wardly away from said member, effecting engagement between the hat and said member to rotate the hat, engaging the hat with an abrading tool, effecting relative movement between the abrading tool and the hat along a path extending between the tip and the brim edge of the hat, and forcing the hat brim against said member as the abrading tool passes over the hat brim so that the hat is continuously and uninterruptedly pounced from tip to brim edge.

8. The method of pouncing a hat which includes in the order named the steps of, mounting a hat in closely spaced relation to a hat rotating member, effecting engagement between said member and a portion of the hat, said hat being partially blocked so that its brim extends outwardly from said member, moving a pouncing tool over said hat along a path extending between the tip and brim thereof, and flattening the brim of the hat against said member during the operation of the pouncing tool on the brim.

9. The method of pouncing a partially blocked hat which includes in the order named the steps of, supporting the hat adjacent but spaced from a rotating block, forcing a portion only of the hat against the block to effect rotation of the hat, continuously abrading the rotating hat along a path extending between the tip to the brim edge of the hat, and flattening the brim of the hat against the rotating block during the abrasion of the brim, the brim being flattened against the block progressively ahead of the abrasion thereof.

10. The method of pouncing a partially blocked hat which includes the steps of, supporting the hat adjacent a rotating block, forcing a portion only of the hat against the block to effect rotation of the hat, continuously abrading the rotating hat along a path extending between the tip and the brim edge of the hat, forcing the brim of the hat against the block immediately before the abrasion of the brim, and holding the brim against the block during the abrasion of the brim.
